COMBINED FEEDING AND COLD DRAWING
MECHANISM FOR HEADING MACHINES
AND THE LIKELee Berkebill, Detroit, Mich., assignor to B. W.
Manufacturing Company, Detroit, Mich., a cor-
poration of Michigan

Application March 16, 1936, Serial No. 69,242

25 Claims. (Cl. 205—4)

The invention relates to heading machines and the like and has for its primary object the obtaining of a construction for feeding the stock to the cut-off mechanism and simultaneously subjecting it to a cold drawing operation. Thus, the machine is adapted to use hot-rolled, as distinguished from cold-drawn material, while the cut-off sections have finished surfaces and are of accurate dimensions. The invention, therefore, consists in the construction as hereinafter set forth.

In the drawings:

Figure 1 is a plan view of my improved mechanism as applied to a heading machine;
15 Figure 2 is a longitudinal section partly in elevation taken substantially on line 2—2 of Figure 1, and showing diagrammatically by dot and dash lines the position of a die for engagement with the stock when the latter is to be drawn through the die;

Figure 3 is a similar view showing the parts in a different position of adjustment;

Figure 4 is a cross-section through the straightening means on line 4—4 of Figure 2;

Figure 5 is a cross-section through the feeding means on line 5—5 of Figure 2;

Figure 6 is a similar section taken on line 6—6 of Figure 2;

Figures 7 and 8 are end elevations showing the shearing and transferring means;

Figures 9, 10, 11 and 12 are views showing the successive operations of the heading means;

Figures 13 and 14 are diagrams illustrating the operating and timing mechanism.

While my improved mechanism is applicable to various types of machines, I have shown it as applied to a heading machine in which A is a bed, B a horizontal reciprocating member traveling in ways C upon said bed, and carrying the vertical reciprocating slide B' to which is fastened the punch block B². The member B is reciprocated by suitable mechanism including the rotary crank shaft E and a connecting linkage F between the same and the member B.

My improved mechanism comprises straightening dies G, a reciprocating feed mechanism H and a drawing or sizing die I. As shown, and as preferably arranged, the stock J, preferably hot-rolled, is first delivered to the straightening dies G; is then engaged by the feeding mechanism H; and is lastly passed through the drawing and sizing die I. This specific arrangement is not absolutely essential, but I prefer the same as it avoids any marring, such as might occur if the

feed mechanism were to engage the stock after passing through the die.

The straightening mechanism G may be of any suitable construction adapted to take out any curvature in the stock as delivered thereto. As shown, it consists of a pair of jaws G¹, G² which are slidably secured in a frame including the side plates G³, G⁴ and spacers G⁵, G⁶. The frame is slideable in ways G⁷ fastened by bolts G¹³ to the bed A. As shown, these ways G⁷ comprise vertically spaced horizontal bars provided in their inner faces at their opposed edges with longitudinally extending slots or channels G¹⁴ that receive vertical ribs G¹⁵ of the side plate G³ of the slideable frame and permit a limited movement thereof. The jaws G¹ and G² are held from endwise movement by keys G⁸ engaging the plates G³ and G⁴. The lower jaw G² is adjusted vertically by two spaced set screws G⁹ which permit of properly aligning it with the work, and the jaw G¹ is adjusted by a single set screw G¹⁰. Thus, these jaws can be clamped upon the work with just sufficient pressure to perform the straightening operation and to give the necessary resistance against back feeding. The sliding movement of the frame is limited by stops G¹¹. These are preferably set screws which threadedly engage lugs G¹⁶ of the ways G⁷ in the path of the plate G³ forward and in rear thereof. These stops may be adjusted in the lugs G¹⁶ to prevent the straightener from being carried backward during the rearward movement of the feed mechanism.

The feed mechanism H comprises a pair of plates H¹ and H² with intermediate spacer members H³ and H⁴, these parts being secured to each other by bolts H⁵. The members H³ and H⁴ have oppositely inclined inner edges, while their outer edges are formed into racks H⁶. Shoes H⁷ secured to the bed by bolts H⁸ engage the upper and lower edges of the inner plate H¹ to form guideways therefor. Within the space between the members H³ and H⁴ are arranged a pair of jaw members H⁹ and H¹⁰ which are wedge shaped and have their outer edges arranged parallel to the inclined inner edges of the members H³ and H⁴. Rolls H¹¹ are arranged between the parallel faces of the jaw members and the members H³ and H⁴, and springs H¹² bearing against the large ends of the wedged jaw members H⁹ and H¹⁰ yieldably press the same in a rearward direction. The whole construction constitutes a frictional one-way clutch which will cause the jaw members H⁹ and H¹⁰ to grip the work when moving in a forward direction and to release it when

moving in a rearward direction. This forward and reverse movement is effected by pinions H^{13} which engage the rack members H^6 and are mounted on shafts H^{14} carried by the bed. The plates H' and H^2 extend respectively above and below the racks H^6 so that the pinions H^{13} hold the same from lateral movement. The arrangement is such that when motion is imparted to the pinions H^{13} in the direction indicated by the arrows in Figure 2, the jaws will grip the stock and feed it forward, while upon a reverse rotation of the pinions as indicated by the arrows in Figure 3 the stock will be released and the plates and jaws will be moved rearward. The shafts H^{14} are connected to each other by intermeshing gears H^{15} and one of these gears is actuated by mechanism to be hereinafter described.

The sizing die I may be of any suitable construction adapted to slightly reduce the diameter 20 of the stock when pressed therethrough and to impart thereto a finished surface. This die is mounted on the bed in alignment with the straightening dies G and feed mechanism H, and a tank I' adjacent to the die contains a suitable 25 lubricant for reducing friction during the drawing operation and for coating the stock to facilitate the heading operations. There is also an upwardly opening tank G^{12} of sheet metal receiving and forming a jacket for the straightening 30 mechanism G and containing a lubricant for the stock in passing therethrough. Preferably this tank is held in place by the bolts G^{13} used to fasten the ways G' to the bed A and has suitable 35 openings for receiving the stops G^{11} .

35 Forward of the die I in the direction of feed there is a cut-off mechanism which is associated with other elements of the particular machine to which the cut-off blanks are to be fed. If this machine is, as shown, a heading machine, the 40 stock is cut into suitable lengths and then transferred laterally to a heading die. The specific construction of this heading machine forms no part of the present invention and I shall, therefore, only describe it generally. Mounted on the 45 bed is a member J' apertured for the passage of the stock therethrough and forming one member of a shear. The cooperating member J^2 of the shear is mounted to slide transversely across the 50 face of the member J' and in so doing to sever the projecting portion of the stock. The member J^2 has secured thereto a resilient clip J^3 which 55 yieldably holds the cut-off blank during transfer of the same into alignment with the heading die and punch members K, K' and K^2 . These members are adapted to engage the blank after 60 which it will be released by the clip J^3 and the latter together with the member J^2 will be returned to initial position. It is desirable to provide means for very accurately gaging the length 65 of the cut-off blanks. This might be accomplished by regulating the angle of oscillation of the pinions H^{13} , but it would be difficult to accomplish this with the degree of accuracy required. I, therefore, adjust the angle of oscillation to slightly greater than the length of feed 70 required and subsequently feed the stock backward. This is accomplished by an adjustable stop L which in one position is in alignment with the projecting portion of the stock and during the movement of the head B will bear against the outer end of said projecting portion and feed it 75 backward. The stop L is attached to a block L' which in turn is adjustably mounted on punch block B^2 . In operation block B^2 is moved vertically from a position where the stop L aligns

with the stock to a position out of alignment therewith. The stop L is preferably provided with a screw threaded shank engaging the block L' and a locknut L^2 serves to hold this shank in each position of adjustment.

5 The general operation of the mechanism is as follows:

The shaft E has a crank or eccentric E' thereon which is connected by a rod F with the reciprocating member B. The shaft E also has a gear wheel E^2 which drives an intermeshing gear wheel E^3 in a 1 to 2 ratio. The gear wheel E^3 is on a shaft E^4 which extends to the opposite side of the machine and on each end of this shaft is a variable throw crank. On one end the crank O has a slot O' for engaging a crank pin O^2 which is adjustable radially in said slot to increase or diminish the throw thereof. This pin is connected by a rod O^3 with a bell crank lever O^4 and with a corresponding adjustable crank pin O^6 on the actuating arm of said lever. The other arm of the lever is connected by a coupling pin O^6 with one of the gears H^{15} , the arrangement being such that for two revolutions of the crank shaft E, one revolution is imparted to the crank O and one reciprocation to the rod O^3 and bell crank lever O^4 . Also, when the coupling pin O^6 is in engagement with the gear H^{15} , the latter and the shafts H^{14} and pinions H^{13} will be oscillated through an arc varying according to the adjustment of the cranks.

30 On the opposite end of the shaft E^4 is a variable throw crank P similar to O, the crank pin of which is connected by a rod P' with a slide P^2 . This slide has a cam slot P^3 which engages a pin P^4 on the shank of the shear member J^2 . Thus, each two revolutions of the crank shaft E will effect one reciprocation of the shear J^2 , and the slot P^3 is suitably fashioned to give the desired timing of this movement.

40 At an intermediate point on the shaft E^4 is mounted a cam Q which actuates a reciprocating member Q' connected to a rock arm Q^2 on a rock shaft Q^3 which has an arm Q^4 for actuating the slide B' . The cam Q is so fashioned as to intermittently raise and lower the slide B' with a dwell at each end of the movement thereof.

45 With the mechanism as described, it will be understood that two reciprocations are imparted to the slide B to each reciprocation of the shear J^2 and of the slide B' . Also, that while the shear J^2 is stationary in the position shown in Figure 1, the stock is advanced by the feed mechanism a length slightly greater than that required for the blank and is then fed backward by the gage stop L which impinges thereagainst. This will exactly determine the length to be cut off after which the shear J^2 is actuated to effect the cut-off and to transfer the blank into alignment with the punch and dies.

50 In the complete operation, each forward movement of the feed mechanism H will first grip the stock between the jaws H^9 and H^{10} and then move it forward an amount determined by the adjustment of the cranks O' and O^6 . During 55 this movement, the stock is drawn through the jaws of the straightening dies G' and G^2 , and it is also pressed forward through the sizing die I which latter is formed of exceedingly hard material, such as tungsten carbide. After the completion of the forward movement and during the rearward movement of the feeder H, the stop L which is in alignment with the projecting portion of the stock will contact therewith and effect 60

a slight rearward movement. This is permitted by the sliding of the frame of the straightening dies G' and G², while the die I will offer sufficient frictional resistance so as to prevent any over-
 5 feeding in this reverse direction. It will thus be appreciated that during each cycle, hot-rolled stock, preferably delivered from a coil, is fed forward being first straightened and subsequently delivered to the sizing die I through which it
 10 passes, and thence through the member J' to project outward beyond the same. The projecting portion is then pressed rearward by the stop L and subsequently sheared off and delivered to the heading die.
 15 If, at any time, there should be necessity for stopping the feeding of the stock, this may be quickly accomplished by withdrawing the pin O⁶ which will disengage the bell crank O⁴ from the gear wheel H¹⁵ and will, therefore, stop the oscillation of the gear pinions H¹³. If desired, a sizing die such as X designated diagrammatically by dot and dash lines in Figure 2 may be rigidly mounted upon the bed A between the straightening mechanism G and the feed mechanism H. In this instance the stock J would be drawn by the feeding mechanism H through the sizing die X after passing through the straightening mechanism G. When such a sizing die X is located as desired, the sizing die I may be used as an additional die or dispensed with entirely, as desired. Otherwise, the structure would be the same as that previously described.

What I claim as my invention is:

1. In mechanism of the class described, a sizing die, work straightening means, and means for feeding work from the straightening means to the die, including a pair of opposed work-engaging jaws movable relative to each other to alternately grip and release the work, reciprocating side plates for said jaws, spacers for said plates above and below said jaws and having inclined portions, means engaging said inclined portions and operable upon movement of said plates in one direction to cause the jaws to grip the work, and means operable upon movement of said plates in the opposite direction to cause the jaws to release the work.
 2. In mechanism of the class described, a sizing die, work straightening means, and means for feeding work from the straightening means to the die, including a pair of opposed work-engaging jaws movable relative to each other to alternately grip and release the work, reciprocating side plates for said jaws, spacers for said plates above and below said jaws, means for reciprocating said plates including racks carried by said spacers, and oscillating pinions engaging said racks.
 3. In mechanism of the class described, a sizing die, work straightening means, and means for feeding work from the straightening means to the die, including a pair of opposed work-engaging jaws movable relative to each other to alternately grip and release the work, reciprocating side plates for said jaws, spacers for said plates above and below said jaws, means for reciprocating said plates including racks carried by said spacers, pinions engaging said racks, shafts for said pinions, intermeshing gears on said shafts, a reciprocating driver, and a connection between said driver and one of said intermeshing gears for imparting an oscillating motion to said pinions.

4. In mechanism of the class described, a sizing die, work straightening means, and means for feeding work from the straightening means to the

die, including a pair of opposed work-engaging jaws movable relative to each other to alternately grip and release the work, reciprocating side plates for said jaws, spacers for said plates above and below said jaws, means for reciprocating said plates including a rack rigid with said plates, and an oscillating pinion engaging said rack.

5. In mechanism of the class described, a sizing die, work straightening means, and means for feeding work from the straightening means to the die, including a pair of opposed work-engaging jaws movable relative to each other to alternately grip and release the work, reciprocating side plates for said jaws, spacers for said plates above and below said jaws, means for reciprocating said plates including racks carried by said spacers, and oscillating pinions engaging said racks, said plates extending above and below the racks whereby the pinions hold the same against lateral displacement.

6. In mechanism of the class described, a sizing die, means for feeding work to said die, and means for straightening said work for proper engagement with said feeding means and die, including a pair of slideable work-engaging jaws, a slideable supporting frame for said jaws including a pair of spaced side plates, and spacers between said plates, actuating means for said jaws carried by said spacers, and means engageable with one of said plates to limit sliding movement of said frame.

7. In mechanism of the class described, a sizing die, means for feeding work to said die, and means for straightening said work for proper engagement with said feeding means and die, including a pair of slideable work-engaging jaws, a supporting frame for said jaws including side plates upon opposite sides of said jaws, spacers between said plates above and below said jaws, and adjusting means for the jaws including adjustable means carried by said spacers and engaging said jaws.

8. In mechanism of the class described, a sizing die, means for feeding work to said die, and means for straightening said work for proper engagement with said feeding means and die, including a pair of work-engaging jaws, a slideably mounted supporting frame for said jaws, means carried by the frame holding the jaws against endwise movement while permitting movement of the jaws relative to each other, and means also carried by the frame for moving said jaws relative to each other.

9. In mechanism of the class described, a sizing die, and means for causing work to be moved through said die including a pair of cooperating work-engaging jaws movable relative to each other to alternately grip and release the work and reciprocable in unison toward and from said die, and means for effecting reciprocation of said jaws, including a pair of spaced oscillating shafts, a carrier for said jaws mounted to slide between said shafts, means for translating motion from said oscillating shafts to said carrier, and means for translating motion from said carrier to said jaws.

10. The combination with a bed, of reciprocating stock feeding means mounted thereon, said means comprising a reciprocating frame slideable on the bed, racks on opposite longitudinal edges of said frame, oscillating pinions intermeshing with said racks for reciprocating said frame, a one-way clutch carried by said frame and including jaws operable automatically to grip the stock when the frame is moving in one direction and

- operable automatically to release the stock when the frame is moving in the other direction, and means for oscillating said pinions synchronously to reciprocate said frame.
5. 11. In mechanism of the class described, a sizing die, work straightening means, and means for feeding work from the straightening means to the die including a pair of opposed work-engaging jaws movable relative to each other to alternately grip and release the work, reciprocating side plates for said jaws, means for reciprocating said plates including racks carried by said plates, and oscillating pinions engaging said racks, said plates extending above and below the racks whereby the pinions hold the same against lateral displacement.
10. 12. In mechanism of the class described, a sizing die, and means for moving work through the die, including a pair of opposed work-engaging jaws movable relative to each other to alternately grip and release the work, said jaws having longitudinally extending inclined portions, reciprocating members having inclined portions substantially parallel to the inclined portions of said jaws, means engaging the inclined portions of said jaws and members and operable upon movement of said members in one direction to cause the jaws to grip the work, and means engaging the adjacent ends of said jaws and operable upon movement of said members in the opposite direction to cause the jaws to release the work.
15. 13. In mechanism of the class described, a die for the stock, and means for moving stock relative to the die, including a reciprocating frame, racks on the frame at opposite longitudinal edges thereof, oscillating pinions intermeshing with said racks for reciprocating said frame, a one-way clutch carried by said frame and including jaws operable automatically to grip the stock when the frame is moving in one direction and operable automatically to release the stock when the frame is moving in the other direction, and means for oscillating said pinions synchronously to reciprocate said frame.
20. 14. In mechanism of the class described, a die for the work, and means for moving work relative to the die, including a pair of opposed stock-engaging jaws movable relative to each other to alternately grip and release the work, reciprocating side plates for said jaws, spacers for said plates above and below said jaws and having inclined portions, means for reciprocating said plates including a rack carried by one of said spacers and an oscillating pinion engaging said rack, means engaging the inclined portions of the spacers and operable upon movement of said plates in one direction to cause the jaws to grip the work, and means operable upon movement of said plates in the opposite direction to cause the jaws to release the work.
25. 15. In mechanism of the class described, a die for the work, and means for moving work relative to the die, including a pair of opposed work-engaging jaws movable relative to each other to alternately grip and release the work, reciprocating side plates for said jaws, spacers for said plates above and below said jaws, means for reciprocating said plates including racks carried by said spacers, and oscillating pinions engaging said racks.
30. 16. In mechanism of the class described, a die for the work, and means for moving work relative to the die, including a pair of opposed work-engaging jaws movable relative to each other to al-
- ternately grip and release the work, reciprocating side plates for said jaws, spacers for said plates above and below said jaws, means for reciprocating said plates including racks carried by said spacers, pinions engaging said racks, shafts for said pinions, intermeshing gears on said shafts, a reciprocating driver, and a connection between said driver and one of said intermeshing gears for imparting an oscillating motion to said pinions.
35. 17. In mechanism of the class described, a die for the work, and means for moving work relative to the die, including a pair of opposed work-engaging jaws movable relative to each other to alternately grip and release the work, reciprocating side plates for said jaws, spacers for said plates above and below said jaws, means for reciprocating said plates including racks carried by said spacers, and oscillating pinions engaging said racks, said plates extending above and below the racks whereby the pinions hold the same against lateral displacement.
40. 18. In mechanism of the class described, the combination with a bed, of ways secured to said bed, and work straightening means carried by said bed and including a pair of slidable work-engaging jaws, a supporting frame for said jaws slidable in said ways and including a pair of spaced side plates and spacers between said plates, and actuating means for said jaws carried by said spacers.
45. 19. In mechanism of the class described, the combination with a bed, of ways secured to said bed, and work straightening means carried by said bed and including a pair of slidable work-engaging jaws, a supporting frame for said jaws slidable in said ways and including a pair of spaced side plates and spacers between said plates, and means for limiting sliding movement of the frame including adjustable means carried by said ways.
50. 20. In mechanism of the class described, the combination with a bed, of ways secured to said bed, and work straightening means carried by said bed and including a pair of slidable work-engaging jaws, a supporting frame for said jaws slidable in said ways and including a pair of spaced side plates and spacers between said plates, and means for limiting sliding movement of the frame relative to the bed including means carried by said ways and engageable with one of said plates.
55. 21. In mechanism of the class described, a sizing die, means for moving work in a forward direction through the die, including a pair of opposed work-engaging jaws movable relative to each other to alternately grip and release the work, said jaws having longitudinally extending inclined portions, reciprocating members having inclined portions substantially parallel to the inclined portions of said jaws, and anti-friction means between and engaging said parallel portions, said jaws, reciprocating members and anti-friction means forming a one-way clutch operable to cause the jaws to grip the work when moving in a forward direction and to release the work when moving in a rearward direction, and spring means bearing against the forward end of said jaws and yieldably pressing said jaws in a rearward direction.
60. 22. In mechanism of the class described, a sizing die, and means for moving work through said die, including a pair of opposed work-engaging jaws movable relative to each other to alternately grip and release the work, the outer edges of said jaws having longitudinally extending inclined

portions, reciprocating side plates upon the outer sides and free of said jaws, spacers for said plates adjacent the outer edges of said jaws, the inner edges of said spacers having longitudinally extending inclined portions substantially parallel to the inclined portions of said jaws, said spacers being rigid with said plates, anti-friction means between and engaging the parallel inclined portions, and spring means bearing against one end 5 of said jaws, the elements aforesaid of said moving means forming a one-way clutch for causing said jaws to grip the work when moving in one direction and to release the work when moving in the opposite direction.

15 23. In mechanism of the class described, a sizing die, and means for moving work through said die, including a pair of opposed work-engaging jaws movable relative to each other to alternately grip and release the work, reciprocating plates 20 upon the outer sides and free of said jaws, spacers between said plates and disposed adjacent the outer edges of said jaws, said spacers being fixed to said side plates, the outer edges of said spacers being provided with racks, the inner edges of said 25 spacers being provided with inclined surfaces, the outer edges of said jaws being provided with inclined surfaces substantially parallel to the inclined surfaces of said spacers, anti-friction means between and engaging said parallel surfaces, and spring means bearing against one end 30 of said jaws, the elements aforesaid of said moving means forming a one-way clutch for causing

the jaws to grip the work when moving in one direction and to release it when moving in the opposite direction, and actuating means for said moving means including pinions engaging said racks. 5

24. In a machine of the class described, a pair of opposed stock clamping jaws, a reciprocating head carrying the jaws and having wedge surfaces for moving the jaws transversely of the head to clamped position against the stock, and a spring movable lengthwise of the head against one end of the jaws to hold the latter wedged by said surfaces against the stock. 10

25. In mechanism of the class described, a sizing die, and means for moving work through said die, including a pair of opposed work-engaging jaws movable relative to each other to alternately grip and release the work, said jaws having longitudinally extending inclined portions, reciprocating side plates adjacent and free of said jaws, 20 spacers for said plates adjacent said jaws, said spacers having longitudinally extending inclined portions substantially parallel to the inclined portions of said jaws, anti-friction means between and engaging the parallel inclined portions aforesaid, and spring means bearing against one end of said jaws, the elements aforesaid of said moving means forming a one-way clutch for causing said jaws to grip the work when moving in one direction and to release the work when moving 25 in the opposite direction. 30

LEE BERKEBIL,
